UNITED STATES PATENT OFFICE.

ELLEN M. STUBBS, OF PHILADELPHIA, PENNSYLVANIA.

DESIGN FOR A FRUIT SPOON-KNIFE.

44,737.

Specification for Design.

Patented Oct. 14, 1913.

Application filed August 6, 1913. Serial No. 783,420. Term of patent 7 years.

To all whom it may concern:

Be it known that I, ELLEN M. STUBBS, a citizen of the United States, residing in the city and county of Philadelphia and State of Pennsylvania, have invented a new, original, and ornamental Design for Fruit Spoon-Knives, of which the following is a specification, reference being had to the accompanying drawing, forming part thereof.

The figure is a perspective view of a fruit spoon-knife, showing my new design.

I claim:—

The ornamental design for a fruit spoon-knife as shown.

ELLEN M. STUBBS.

Witnesses:

JAMES W. CARPEUL,
A. E. SEAMAN.
